LASTING MACHINE

Joseph Fossa, Salem, Mass., assignor to United
Shoe Machinery Corporation, Flemington, N. J.,
a corporation of New Jersey

Application July 2, 1945, Serial No. 602,698

20 Claims. (Cl. 12—1)

1

This invention relates to shoe machines and particularly to improvements in lasting machines of the type disclosed and claimed in United States Letters Patent No. 2,411,827, issued in my name on November 26, 1946. It is to be understood, however, that features of the present invention are not limited in their utility to use in this type of machine.

The machine of the above-mentioned patent is provided with a rapidly reciprocating gripper for seizing the lasting margin of the stock to be lasted, in different locations successively along the edge of the shoe bottom, and for tensioning it heightwise of the shoe by pulling it inwardly from the edge of the shoe bottom in a direction substantially parallel to the shoe bottom and over a protective shield portion of a shoe bottom rest; a presser-feed member, operating in time relation to the gripper, for pressing and pounding the overdrawn lasting margin of the stock into adhering relation with the shoe-bottom part and also movable, thereafter, in a direction to feed the shoe; and a feed-retaining member for preventing retrograde movement of the shoe and for retaining previously overlasted stock from being displaced by the next succeeding action of the gripper. It will be understood, in the specification and in the claims appended thereto, as in my prior patent mentioned above, that the term "lasting" is used in a somewhat broadened sense and is intended to include not only the conventional lasting operation but also other analogous operations such, for example, as the working of the margin of a platform cover over a platform, while the term "lasting margin" is intended to include that portion of a platform cover, or other shoe part, which corresponds to a like portion of the upper stock of a conventional shoe.

As already stated, the stock is tensioned over the protective shield portion of a bottom rest, and to facilitate the introduction of work to the machine this bottom rest is, in accordance with a feature of the invention, movable by spring means to an inoperative position, operator-controlled means being provided for returning the bottom rest to operative position, against the action of the spring means, in which its shield portion will engage the bottom of a shoe held thereagainst, by the operator, close to its marginal edge. This operator-controlled means is also adapted to hold the front gripper jaw in its forward position and away from the reciprocating rear jaw, thus further facilitating the insertion of the lasting margin of the stock between the jaws.

As explained above, in this type of machine,

2

the stock to be lasted in tensioned heightwise of the shoe by the grippers which pull it inwardly from the edge of the shoe, in a direction substantially parallel to the bottom of the shoe, and over a shield portion of a bottom rest which not only serves as means for changing the direction of the force applied to the stock, so that the pull parallel to the shoe bottom results in a tensioning of the stock in a direction heightwise of the shoe, but also protects the edge of the shoe bottom element, such, for example, as a soft platform, from distortion. During the action of the grippers, the inside face of the lasting margin of the stock is drawn quite tightly against a part of the bottom rest adjacent to its shield portion and considerable frictional resistance to movement of the stock thereover is produced. Especially is this so where the inside face of the lasting margin is coated with an adhesive. This frictional resistance must, of course, be overcome by the gripper, in addition to the force for tensioning the stock, and the pull necessary to overcome this frictional resistance, and also adequately to tension the stock, in some instances becomes quite large and may approach the tearing strength of the material.

It is therefore an object of this invention to provide, in a lasting machine of this type, means for facilitating the lasting operation by eliminating the frictional resistance of the part of the bottom rest, adjacent to the shield portion, on the lasting margin of the stock, as it is being pulled inwardly thereover by the gripper and/or applying to the stock an additional pull in a direction to assist the gripper in tensioning the stock. To this end, the herein illustrated machine is provided with a bottom rest having a rotary member for engaging the lasting margin of the stock as it is drawn inwardly by the gripper. This member comprises a rotary spindle so mounted adjacent to the shield portion of the bottom rest as to engage the lasting margin of the stock as it is being acted on by the gripper and to serve as an anti-friction means. Preferably, and as herein shown, this spindle is power driven at a high speed so that its surface moves at a rate somewhat in excess of the linear speed of movement of the stock. When so driven, the spindle, in addition to the anti-friction action, mentioned above, exerts on the lasting margin a frictional drag that augments the pulling action of the gripper and the tensioning of the stock is correspondingly increased. This spindle is tapered and is inclined downwardly and inwardly of the machine, and lengthwise of the shoe, to, and

preferably a little beyond, the edge of the shoe bottom. With the spindle thus positioned it has a tendency to move the stock away from the edge of the shoe bottom, to which it may have become accidentally adhered, before it is acted on by the gripper, thus further facilitating the lasting operation.

In the machine of the mentioned application, treadle-operated means are provided for moving the lasting shield and bottom rest from an inoperative position, in which it is held by a spring, to its operating position, and associated with the bottom rest is means for holding the front gripper jaw in an inoperative position against the action of a relatively strong gripper-closing spring. This arrangement necessitates the use of a strong treadle spring which results in a rather hard treadle action that may be tiring to the operator. Therefore, and in accordance with a further feature of this invention, the herein illustrated machine is provided with novel and improved means for actuating the bottom rest and for holding the front gripper jaw in its inoperative position. As shown, the bottom rest is operated through a toggle which is straightened by the depression of the treadle, against the action of a relatively light treadle spring, which breaks the toggle and moves the bottom rest to its inoperative position when the treadle is released. The means for holding the front gripper jaw in its inoperative position, when the treadle is released, is likewise actuated through the toggle and arranged to shift the anchorage for the gripper-closing spring. Thus only a very light toggle-breaking spring opposes the depression of the treadle and a very easy action is obtained. Also, the bottom rest is held, by the straightened toggle, quite rigidly in its operative position, where it must oppose the horizontal pull of the gripper.

These and other objects and features of the invention will become apparent from the following detailed description of the embodiment thereof shown in the accompanying drawings and will be pointed out in the claims.

In the drawings,

Fig. 1 is a view in side elevation of a machine of the type disclosed in the above-mentioned application provided with the features of this invention, a portion of the head and other parts being broken away to facilitate the disclosure;

Fig. 2 is a view in front elevation of a portion of the machine shown in Fig. 1; and

Figs. 3 and 4 are detail views, at an enlarged scale, of the operating elements of the machine shown in Fig. 1, Fig. 3 being in side elevation and Fig. 4 in plan.

Referring to the drawings, the operating instrumentalities of the illustrated machine are, with the exceptions to be noted below, the same as those of the machine of the mentioned patent and comprise a gripper, including a rear gripper jaw 10 and a front gripper jaw 12, for seizing the lasting margin of the stock and applying lasting stress thereto; a shoe bottom rest and lasting shield 14 for engaging and positioning heightwise the bottom of a shoe and over which the lasting margin is drawn by the stress applied thereto by the gripper; a presser-feed member 16 for pressing the tensioned lasting margin down onto the bottom of the shoe and for exerting a feeding force on the shoe; a feed-retaining member 18 for holding the shoe against retrograde movement during the return, or back-feeding, move-

ment of the presser-feed-foot; and an edge gage roll 20 for positioning the shoe laterally. These instrumentalities are all mounted on, and operated by mechanism contained within, a hollow head construction 22 comprising a lower portion 24 and a removable top part 26 secured thereto by means of cap screws 28, 28.

The rear gripper jaw 10 is attached, by means of a clamping bolt 30, to the forward end of a carrier 32 which is supported by two rocker arms 34, 36 journaled respectively on fixed cross shafts 38 and 40 that extend across the lower portion 24 of the head 22. This carrier is pivotally secured to these rocker arms by means of studs 42, 44 and is movable forwardly and rearwardly of the machine by means of a third rocker arm 46 that extends upwardly from a hub member 48 common to it and to the rocker arm 36. The rocker arms 34 and 36, together with that part of the carrier 32 which extends between said arms, constitute a parallel motion linkage so that the carrier always remains horizontal during its forward and rearward movements. As in the machine of the above-mentioned application the rocker arm 46 is oscillated, to impart forward and rearward movements to the carrier 32, by means of an eccentric, not shown, which is mounted on a main drive shaft 52 and connected to the rocker arm 46 by an arm 62.

The front gripper jaw 12 is secured, by means of a clamp nut 100 and washer 101, on the outer end of an elongated rod 102 which is slidably mounted in bearing bores 104, 106 formed in bosses 108, 110 on the carrier 32. The jaw 12 fits into a hole 105 formed in an enlarged portion 107 of the rod 102, which beyond this enlarged portion is reduced in diameter to receive the washer 101 and is threaded for the clamp nut 100. At its back end this rod abuts a second rod 103 which is reciprocated in time relation to the rearward and forward movements of the carrier 32 by mechanism, not here shown but like that disclosed in the mentioned application. The rod 102, which carries the front gripper jaw 12, is urged rearwardly of the machine by means of a coil spring 150 that extends between the upper end of the front gripper jaw and an arm 152. Referring to Fig. 1, as the shaft 52 is rotated, the carrier 32, together with the rear gripper jaw 10, moves to the left, forwardly of the machine, and at the same time the rod 103 is shifted to the right, permitting the front gripper jaw to approach, and eventually meet, the forwardly moving rear gripper jaw 10. As the rear gripper jaw continues its forward movement, the spring 150 will be tensioned as the two gripper jaws move forwardly of the machine until the completion of the movement of the carrier 32 in this direction. During this time, movement of the rod 103 to the right is completed and this rod then is shifted quickly to the left so that when the carrier and rear gripper jaw begin their backward movement the rod 103 engages the end of the rod 102 and causes the front gripper jaw to move somewhat further to the left, the rod 103 holding the front gripper jaw in this position until the next forward movement of the rear gripper jaw begins.

As is explained in the mentioned patent, the gripper jaws are closed on the stock to be lasted by means of the spring 150 and draw this stock inwardly from the edge of the platform and over the bottom rest 14, in a direction substantially parallel to the bottom of the shoe, thus tension-

ing the stock in a direction heightwise of the shoe. The arm 152 to which the spring 150 is anchored has a hub 151 which is journaled on a shaft 154 that is rotatably mounted in the top portion 26 of the head of the machine, and extending upwardly from this hub is a second arm 156 provided with a spring-locking plunger 153 which fits into one of several holes 160 formed in the upper end of a third arm 162 which extends upwardly from a hub 161 that is secured to the shaft 154. As will appear below, the shaft 154 is held against rotation during the operation of the machine so that the tension of the spring 150, and accordingly the closing pressure of the gripping jaws on the stock, may be varied by shifting the spring plunger 153 from one hole to another.

As the stock is thus pulled inwardly over, and in a direction substantially parallel to, the bottom of the shoe, it is drawn over the inner end of the bottom rest 14, and also over a portion 170 thereof which is positioned directly below and in alinement with the line of action of the gripper so as to constitute a lasting shield or abutment. Thus the horizontally directed stress applied by the gripper is transposed into a vertical pull for tensioning the stock in a direction perpendicular to the shoe bottom and, at the same time, distortion of the shoe bottom member prevented. The bottom rest and lasting shield 14 are mounted for movement outwardly away from the edge gage roll 20, for the purpose of facilitating the beginning of a lasting operation, in the following manner. The bottom rest and lasting shield is removably secured by screws 164 to an elongated cylindrical member 166 which itself is secured, by bolts 168, to an arm 174 that is journaled on a shaft 178 supported in a forwardly projecting portion of the head part 26. Also journaled on this shaft is a hub member 180 from which project two arms 182 and 184, the former being curved so as to extend rearwardly of the machine and at its end carrying a link 186 which is connected by a pin 187 to an arm 188 extending upwardly from a hub 190 that is secured to a shaft 192; see Fig. 1. This shaft is journaled in the head portion 26 and extends beyond one side thereof where it carries a lever 194 to which is secured a link 196, see Fig. 2. The hub of the lever 194 has spaced stop projections 191 and 193 which are adapted to engage a stop pin 195 that projects outwardly from the head portion 26. The arm 174 extends above the shaft 178 and is adjustably connected to the arm 182 by means of a clamp screw 181 and slot 183. When the link is moved to the position shown in Fig. 1, by the depression of a treadle, not shown, the toggle formed by the link 186 and the arm 188 is straightened and the bottom rest 14 moved to its operative position, the stop 191 engaging the pin 195. Upon release of the treadle a spring, not shown, moves the link upwardly, thus breaking the above-mentioned toggle, and swinging the arm 174 in a clockwise direction, to move the bottom rest outwardly to its inoperative position, the stop 193 now engaging the pin 195.

Secured to the arm 184 is a link 189 that extends rearwardly of the machine where it is connected to an arm 197, which extends downwardly from the hub 161 that carries the arm 162. This arm has at its lower end an offset projection 199 that is in line with a collar 200 on the rod 102. When the treadle is released, this projection engages the collar 200 and the

front gripper jaw is thus held in its extreme forward position. Also, since the arm 197 and arm 162 are secured to the shaft 154, the arm 152 will be swung in a clockwise direction to relieve the tension of the gripper-closing spring 150. With this arrangement, only a relatively light treadle spring is required and the treadle action is very easy. Also, when the treadle is depressed, the bottom rest is held in its operative position, where, as already noted, it must oppose the horizontal stress applied by the gripper, quite rigidly by the straightened toggle link 186 and arm 188, and without any extra effort on the part of the operator.

15 The stock which has been tensioned and drawn inwardly over the shoe bottom by the gripper in the manner above explained is pressed firmly against the bottom of the shoe, and into lasted position thereon, just as it is released by the gripper, by means of the presser-feed-member, or presser-feed-foot, 16, which thereafter, and while in engagement with the stock, is moved laterally to feed the shoe. This presser-feed-foot 16 is adjustably secured by a screw 240 to the outer end of a lever 242 which is pivotally mounted by means of a stud 241 on an upwardly extending arm 244 formed integrally with a shaft 246 that is journaled in a portion of the head of the machine. The lever 242 is oscillated, in time relation to the operation of the grippers, to move the presser-feed-foot 16 against the stock, by means of an eccentric, not shown, carried by the shaft 52, and the shaft 246 is oscillated, to move the presser-feed-foot back and forth in a direction extending lengthwise of the shoe, by means of an angle crank, not shown, also mounted on the shaft 52. The action of the presser-feed-foot 16 to press the overdrawn lasting margin against the shoe bottom and, thereafter, to feed the shoe, is the same as set forth in the above-mentioned patent and need not be further explained here.

The shoe is held against retrograde movement during the return, or back-feeding, movement 45 of the presser-feed-foot 16, and lifting of the stock by the next succeeding pulling action of the gripper is prevented, by the feed-retaining member 18. The member 18 is constructed and arranged as in the machine of the above-men- 50 tioned patent and is operated in the same manner from an eccentric, not shown, on the main drive shaft 52.

In the machine of the mentioned patent, the bottom rest has a surface, inclined downwardly 55 and inwardly of the machine, which is located adjacent to the shield portion thereof. As the stock is pulled over the bottom of the shoe, inwardly from the edge of the shoe bottom, the lasting margin is drawn quite tightly against this top surface and also against the shield portion with the result that there is considerable friction between the stock and the bottom rest tending to resist the movement of the stock inwardly of the shoe bottom, particularly when that surface 60 of the stock engaging the bottom rest is coated with a tacky adhesive. In order to eliminate the resulting frictional resistance, which makes it more difficult properly to tension the stock, the herein illustrated machine is provided with a rotary spindle 320 having a tapered lower end 322, which occupies substantially the same position as the mentioned surface, and over which the lasting margin of the stock rides as it is being tensioned by the gripper. As shown in Figs. 1, 3 65 and 4, this spindle is inclined downwardly and

inwardly of the machine, and lengthwise of the shoe, so that its tapered lower end extends down to the under side of the bottom rest and close to the shield portion 170 at the edge of the shoe.

The spindle 320 is journaled in a bearing bore 324, formed in the elongated cylindrical member 166, on the upper end of which is mounted a gear housing 326 that contains two meshing spiral gears 328 and 330. The gear 328 is secured to the upper end of the spindle 320 while the gear 330 is secured to a shaft 332, journaled in an extension 323 of the housing 326, that is connected by a universal joint 334 to an elongated shaft 336. The shaft 336 is in turn connected, by a universal joint 338, to a shaft 340 journaled in a gear housing 342 mounted on the head of the machine by screws 334, which carries a spiral gear 346 that meshes with gear teeth 348 formed directly on the main drive shaft 52. A tubular housing 350 covers the shaft 336 and is mounted at one end in the gear housing 342. The other end of this housing is shaped to fit in a spherical recess 343 in the extension 323 of the gear housing 326. The centers of the universal joint 334 and of the recess 343 are in line with the axis of the shaft 178, see Fig. 1, so that the housing and joint may articulate about this center, when the bottom rest is moved from one position to the other, without subjecting the shaft or its housing to any undue strain.

The operation of the herein disclosed machine is, in general, the same as that of the machine shown in the above-mentioned patent and should be readily understood. It is briefly as follows: Referring to the drawings, when the treadle, not shown, is released, the link 196 will be elevated by the treadle spring, also not shown, thus breaking the toggle link 186 and arm 188. The bottom rest 14 will now be swung to the left from the position shown in Fig. 1, and the front gripper jaw held in its forward position, away from the rear gripper jaw, by the offset projection 199 on arm 191, thus facilitating the entry of a work-piece such, for example, as a slip-lasted shoe having a platform P, platform cover C and an upper U on a last L. After the shoe has been placed in the machine with the edge of its platform against the edge gage 20, and with the bottom face of its platform held up against the bottom rest 14, the treadle is released to permit the bottom rest to swing into the position shown in Fig. 3 and the front gripper to move toward the rear gripper jaw. As the lasting operation proceeds, the gripper jaws close on the lasting margin of the cover C and pull it inwardly from the edge of the shoe, thus tensioning it heightwise of the shoe, the presser-feed-foot 16 descends and, just as the grippers open to release the stock, presses the tensioned lasting margin against the bottom face of the platform and, since this face, as well as the inside face of the lasting margin have been previously coated with cement, causes them to adhere. The presser-feed-foot now moves laterally to feed the shoe and thereafter rises. At this time the feed-retaining finger 18 descends to apply additional pressure on the overlasted stock and also to prevent retrograde movement of the shoe during the back-feeding movement of the presser-feed-foot which now occurs. These operations are repeated rapidly as the lasting operation proceeds along the peripheral edge of the shoe.

As will be apparent from an inspection of Figs. 2 and 3, the lasting margin of the stock is drawn against the tapered end 322 of the spindle 320

as it is pulled inwardly over the shoe bottom by the grippers. Preferably, and as herein illustrated, this spindle is rotated from the main drive shaft and the gearing ratio is such that the speed of the surface of the tapered end is somewhat in excess of the rate of movement of the stock by the gripper. Hence, not only is all frictional resistance to the inward movement of the stock, of that portion of the bottom rest adjacent to the shield portion, eliminated, but the pulling action of the gripper is also augmented by the frictional drag which the driven rotary spindle imposes upon the stock which is held tightly against it. As will be apparent, it is not necessary that the spindle be driven in order to eliminate the frictional resistance mentioned above; since, if it is merely allowed to rotate freely, the spindle will serve as an anti-friction member over which the stock may be readily pulled by the gripper.

As will be seen in Figs. 3 and 4, the rotating spindle extends down close to and slightly beyond the marginal edge of the platform P and in this position it has a tendency to lift the lasting margin of the stock before it reaches the gripper. Thus, if the lasting margin should become accidentally adhered to the side face of the platform, as is frequently the case, the rotary spindle will move it away from the side face of the platform and free it for the action of the grippers.

Having described the invention, what I claim as new and desire to secure by Letters Patent of the United States is:

1. A lasting machine having, in combination, tensioning means for pulling the marginal portion of the stock to be lasted inwardly over the bottom of a shoe in different locations successively along the edge of the shoe bottom, and additional means for applying to the stock in each of said locations a frictional pull to tension it heightwise of the shoe in response to the inward pull of said tensioning means.

2. A lasting machine having, in combination, tensioning means for pulling the marginal portion of the stock to be lasted inwardly over the bottom of a shoe, a spindle extending substantially to the edge of the shoe bottom and over which the stock is thus pulled by said tensioning means, and means for rotating said spindle to cause it to exert a frictional pull on said stock to assist in tensioning the stock heightwise of the shoe and inwardly over said shoe bottom.

3. A lasting machine having, in combination, means for engaging the bottom of a shoe adjacent to the marginal edge thereof, tensioning means for drawing the lasting margin of the stock to be lasted inwardly from the edge of the shoe and over the shoe-bottom-engaging means, and anti-friction means associated with the shoe-bottom-engaging means for engaging the stock as it is thus drawn inwardly by the tensioning means.

4. A lasting machine having, in combination, means for engaging the bottom of a shoe adjacent to the marginal edge thereof, tensioning means for drawing the lasting margin of the stock to be lasted inwardly from the edge of the shoe and over the shoe-bottom-engaging means, and rotary anti-friction means mounted on said shoe-bottom-engaging means for engaging the stock and relieving the inward frictional drag on the stock as it is thus drawn inwardly by the tensioning means.

5. A lasting machine having, in combination, means for engaging the bottom of a shoe adjacent to the marginal edge thereof, tensioning means

for drawing the lasting margin of the stock to be lasted inwardly from the edge of the shoe and over the shoe-bottom-engaging means, and power-driven rotary means mounted on said shoe-bottom-engaging means for engaging the stock as it is thus drawn inwardly by the tensioning means.

6. A lasting machine having, in combination, means for engaging the bottom of a shoe adjacent to the marginal edge thereof, rapidly reciprocating gripper means for seizing the lasting margin of the stock to be lasted and for drawing it inwardly from the edge of the shoe over a portion of the shoe-bottom-engaging means in a direction substantially parallel to the bottom of the shoe thereby to tension the stock in a direction normal to the bottom of the shoe, and anti-friction means associated with the shoe-bottom-engaging means for engaging the stock as it is thus drawn inwardly by the gripper means.

7. A lasting machine having, in combination, means for engaging the bottom of a shoe adjacent to the marginal edge thereof, rapidly reciprocating gripper means for seizing the lasting margin of the stock to be lasted and for drawing it inwardly from the edge of the shoe over a portion of the shoe-bottom-engaging means in a direction substantially parallel to the bottom of the shoe thereby to tension the stock in a direction normal to the bottom of the shoe, and rotary means associated with the shoe-bottom-engaging means for engaging the stock as it is thus drawn inwardly by the gripper means.

8. A lasting machine having, in combination, means for engaging the bottom of a shoe adjacent to the marginal edge thereof, rapidly reciprocating gripper means for seizing the lasting margin of the stock to be lasted and for drawing it inwardly from the edge of the shoe over a portion of the shoe-bottom-engaging means in a direction substantially parallel to the bottom of the shoe thereby to tension the stock in a direction normal to the bottom of the shoe, and power-driven rotary means associated with the shoe-bottom-engaging means for engaging the stock as it is thus drawn inwardly by the gripper means.

9. A lasting machine having, in combination, means for engaging the bottom of a shoe adjacent to the marginal edge thereof, tensioning means for drawing the lasting margin of the stock to be lasted inwardly from the edge of the shoe and over the shoe-bottom-engaging means, and a rotary spindle, mounted adjacent to the shoe-bottom-engaging means and inclined downwardly and inwardly of the machine, and lengthwise of the shoe, with its lower end adjacent to the marginal edge of the shoe, for engaging the stock as it is thus drawn inwardly over the shoe-bottom-engaging means by the tensioning means.

10. A lasting machine having, in combination, means for engaging the bottom of a shoe adjacent to the marginal edge thereof, tensioning means for drawing the lasting margin of the stock to be lasted inwardly from the edge of the shoe and over the shoe-bottom-engaging means, and a rotary spindle, mounted adjacent to the shoe-bottom-engaging means and having a tapered end inclined downwardly and inwardly of the machine, and lengthwise of the shoe, to the marginal edge of the shoe, for engaging the stock as it thus is drawn inwardly over the shoe-bottom-engaging means by the tensioning means.

11. A lasting machine having, in combination, means for engaging the bottom of a shoe adjacent

to the marginal edge thereof, tensioning means for drawing the lasting margin of the stock to be lasted inwardly from the edge of the shoe and over the shoe-bottom-engaging means, and a power-driven rotary spindle, mounted adjacent to the shoe-bottom-engaging means and inclined downwardly and inwardly of the machine, and lengthwise of the shoe, with its lower end adjacent to the marginal edge of the shoe, for engaging the stock as it is thus drawn inwardly over the shoe-bottom-engaging means by the tensioning means.

12. A lasting machine having, in combination, means for engaging the bottom of a shoe adjacent to the marginal edge thereof, tensioning means for drawing the lasting margin of the stock to be lasted inwardly from the edge of the shoe and over the shoe-bottom-engaging means, and a power-driven rotary spindle, mounted adjacent to the shoe-bottom-engaging means and having a tapered end inclined downwardly and inwardly of the machine, and lengthwise of the shoe, to the marginal edge of the shoe, for engaging the stock as it is thus drawn inwardly over the shoe-bottom-engaging means by the tensioning means.

13. A lasting machine having, in combination, an edge gage for engaging the side of a shoe to position it in the machine, a shoe-bottom rest, said shoe-bottom rest being movable to an operative position in which it is positioned on and close to the marginal edge of the bottom of a shoe held against the edge gage and to an inoperative position in which it is withdrawn from the edge of the shoe, and means including a toggle mechanism for moving said bottom rest to each of said positions.

14. A lasting machine having, in combination, an edge gage for engaging the side of a shoe to position it in the machine, a shoe-bottom rest, said shoe-bottom rest being movable to an operative position in which it is positioned on and close to the marginal edge of the bottom of a shoe held against the edge gage and to an inoperative position in which it is withdrawn from the edge of the shoe, toggle mechanism associated with said bottom rest, operator-controlled means for straightening said toggle mechanism to move said bottom rest to, and for holding it in, operative position, and spring means for breaking the toggle to move the bottom rest to inoperative position.

15. A lasting machine having, in combination, a shoe-bottom rest movable between operative and inoperative positions, operator-controlled means for moving the bottom rest to said positions, gripper means for tensioning the stock to be lasted comprising a power-operated reciprocating rear gripper jaw, a front gripper jaw movable relatively to the rear gripper jaw, and spring means for urging the front gripper jaw toward the rear gripper jaw, and means for holding the front gripper jaw away from the reciprocating rear gripper jaw and for relieving the tension of said spring means when the bottom rest is in its inoperative position.

16. A lasting machine having, in combination, a shoe-bottom rest movable between operative and inoperative positions, operator-controlled means for moving the bottom rest to said positions, gripper means for tensioning the stock to be lasted comprising a power-operated reciprocating rear jaw, a front gripper jaw movable relative to the rear gripper jaw, and a spring for

11

urging the front jaw toward the rear jaw, said spring being connected at one end to the front gripper jaw and at the other end to a shiftable member, and means associated with said operator-controlled means for holding the front gripper jaw away from the reciprocating rear gripper jaw, and for moving the shiftable member to relieve the tension of said spring, when the bottom rest is in its inoperative position.

17. A lasting machine having, in combination, a shoe-bottom rest movable between operative and inoperative positions, operator-controlled means for moving the bottom rest to said positions, gripper means for tensioning the stock to be lasted comprising a power-operated reciprocating rear gripper jaw, a front gripper jaw, and a spring connected at one end to the front gripper jaw for moving the front gripper jaw toward the rear gripper jaw to cause the gripper means to close on the lasting margin of the stock; abutment means, movable by the operator-controlled means, for holding the front gripper jaw away from the rear gripper jaw when the bottom rest is in inoperative position, and means for adjustably connecting the other end of the said spring to said abutment means.

18. A lasting machine having, in combination, gripper means for tensioning the stock to be lasted comprising a power-operated reciprocating rear gripper jaw, a front gripper jaw movable relatively to the rear gripper jaw, and spring means for urging the front gripper jaw toward the rear gripper jaw, and means for holding the front gripper jaw away from the reciprocating rear gripper jaw and for relieving the tension of said spring means.

19. A lasting machine having, in combination,

12

gripper means for tensioning the stock to be lasted comprising a power-operated reciprocating rear jaw, a front gripper jaw movable relative to the rear gripper jaw, and a spring for urging the front jaw toward the rear jaw, said spring being connected at one end to the front gripper jaw and at the other end to a shiftable member, and operator-controlled means for holding the front gripper jaw away from the reciprocating rear gripper jaw and for moving the shiftable member to relieve the tension of said spring.

15 20. A lasting machine having, in combination, gripper means for tensioning the stock to be lasted comprising a power-operated reciprocating rear gripper jaw, a front gripper jaw, and a spring connected at one end to the front gripper jaw for moving the front gripper jaw toward the rear gripper jaw to cause the gripper means to close on the lasting margin of the stock, abutment means, operator-controlled means for moving the abutment means to hold the front gripper jaw away from the rear gripper jaw, and means for adjustably connecting the other end of said spring to said abutment means.

JOSEPH FOSSA.
